(57) **CLAIM**

I claim the ornamental design for a frame for chair, as shown and described.

DESCRIPTION

FIG. 1 is a front perspective view of a frame for chair showing my new design;

FIG. 2 is a front view thereof;

FIG. 3 is a rear view thereof;

FIG. 4 is a left-side view thereof;

FIG. 5 is a right-side view thereof;

FIG. 6 is a top view thereof; and,

FIG. 7 is a bottom view thereof.

The broken lines illustrating portions of the frame for chair are for environmental purposes only and form no part of the claimed design.

1 Claim, 7 Drawing Sheets(56)
